UNITED STATES PATENT OFFICE.

EDWARD L. STILL, OF NEW YORK, N. Y.

WOOD-CLAMP.

SPECIFICATION forming part of Letters Patent No. 471,909, dated March 29, 1892.

Application filed May 20, 1891. Serial No. 393,410. (No model.)

To all whom it may concern:

Be it known that I, EDWARD L. STILL, of the city, county, and State of New York, have invented a new and Improved Wood-Clamp, 5 of which the following is a full, clear, and exact description.

My invention relates to improvements in wood-clamps, such as are used chiefly for holding glued pieces of wood together while the 10 glue is setting; and the object of my invention is to produce a clamp which may be quickly adjusted to hold the pieces of wood firmly together and prevent them from warping while the pressure is applied to them, and 15 also to provide means for attaching legs to the bed of the clamp, and thus forming a horse of it.

To this end my invention consists in certain 20 features of construction and combinations of parts, which will be hereinafter described and claimed.

Reference is to be had to the accompanying 25 drawings, forming a part of this specification, in which similar figures of reference indicate corresponding parts in all the views.

Figure 1 is a broken plan view of the clamp, showing pieces of wood held in position by it. Fig. 2 is a broken vertical longitudinal section of the device. Fig. 3 is a broken vertical cross-section on the line 3 3 in Fig. 2, and Fig. 4 is a detail inverted perspective view of the tail-stock.

The clamp is provided with a bed 10, having thin flanges 11 projecting from its upper 35 side and a heavier flange 12 at the bottom, the flanges 11 being cut away at intervals, as shown at 11^a, so as to facilitate the attachment of the tail-stock, as hereinafter described, and the flange 12 being adapted to receive the 40 recessed horse-heads 13, which are shaped to fit upon the flange and which have depending side flanges 14. A hollow wedge 15 is arranged centrally between the flanges 14 of the horse-heads, and there is space enough between the 45 wedge and the flanges for the legs 16 of the horse. A thumb-screw 17 extends upward through a vertical aperture in each wedge 15 and through a central screw-threaded aperture in each horse-head 13, so as to impinge 50 upon the flange 12 of the bed 10, and the screw 17 carries a nut 18, which may be adjusted so that when the screw is turned home the nut

will strike against the upper portion of the wedge. It will thus be seen that by tightening the screw and adjusting the nut the wedge 55 may be held upward, so as to clamp the legs 16 between it and the flanges 14 of the horse-head, and the horse-head will also be secured to the bed 10.

A head-stock 19, which is recessed in the center, as best shown in Fig. 2, is held to slide in the upper flanges 11 of the bed, and is moved by a hand-screw 20, which is mounted horizontally and longitudinally on the bed, being held to turn in suitable supports 21. The hand-screw is held in a socket of the head-stock, so that when the hand-screw is turned it will move the head-stock backward and forward, according to the direction in which it is turned. The head-stock 19 carries a vertical screw 22, 70 which is slotted longitudinally, as shown at 23, and which is provided with a nut 24, the nut having a scalloped flange, so that it may be easily operated by the fingers.

A tail-stock 25 is adapted to be fixed upon 75 the bed opposite the head-stock 19, and the tail-stock has a central threaded perforation 26, so that a screw 22, similar to that already described, may be secured in it. The tail-stock is also provided with depending flanges 80 27, which are adapted to embrace the flanges 11 of the bed 10, and on the inner sides of these flanges 27, near the ends, are L-shaped lugs 27^a, which are adapted to drop through the cut-away portions 11^a of the flanges 11, and when 85 the tail-stock is placed upon the bed with the lugs projecting through the parts 11^a the tail-stock may be moved backward slightly upon the bed, and the horizontal portions of the lugs will interlock with the flanges 11^a and 90 thus hold the tail-stock securely in place. The vertical slots 23 in the screws 22 are to accommodate a binding-strip 29, which is intended to hold the pieces 30, which have been glued, the tail-stock being apertured at 28 for 95 the passage of the strip 29.

To operate the clamp, the tail-stock is adjusted upon the bed in the manner described, the pieces 30, which have been previously glued, are placed upon the bed between the 100 head-stock and the tail-stock, the binding-strip 29 is placed in the slots 23 of the screws 22, so that it will rest upon the pieces 30, the nuts 24 are turned down so as to strike the

binding-strip, and the hand-screw 20 is turned up tightly, thus forcing the head-stock firmly against the pieces 30 and crowding them closely together. The natural tendency of 5 the glued pieces when pressed in this manner is to warp and double up in the center; but it will be observed that the binding-strip 29 rests firmly upon them, so that the pieces cannot get out of place, and as a result they will 10 be nicely united.

I have shown the bed secured in horse-heads and mounted upon legs, thus forming a horse; but it is obvious that the bed may be secured 15 to a bench or other support, and that the clamping device may be worked in either case. It will be noticed that the tail-stock may be 20 adjusted at different points on the bed of the device, so that the clamp may be quickly adapted to hold a few pieces of wood or a greater number.

Having thus fully described my invention, I claim as new and desire to secure by Letters Patent—

1. The combination, with the bed having 25 tail and head stocks, each provided with a vertical screw having a longitudinal slot and a nut, of the longitudinally-extending screw mounted on the bed with its inner end engaging the head-stock to operate the same, substantially as shown and described.

2. The wood-clamp comprising a bed, a tail-stock secured thereon, a head-stock held to slide upon the bed, vertically-slotted screws mounted in the head-stock and tail-stock, a 35 binding-strip mounted in the slots of the screws, and nuts for the screws, substantially as described.

3. The combination, with a bed provided along its sides with flanges having cut-away 40 portions, as shown, of a tail-stock adapted to be secured upon the bed, said tail-stock having L-shaped lugs 27^a projecting downward from its lower side, the horizontal rearward

projecting portions of said lugs being adapted to enter the cut-away portions of the bed-flanges and interlock with the flanges, substantially as described. 45

4. The combination, with a bed provided along its sides with flanges having portions cut away, as shown at 11^a, of a tail-stock having depending flanges 27 to embrace the bed-flanges, and L-shaped lugs 27^a alongside the inner faces of the flanges 27 with their horizontal portions projecting rearward to enter the cut-away portion 11^a and engage the 50 flanges of the bed, substantially as described.

5. The combination, with a flanged bed carrying clamping mechanism, as shown, of horse-heads secured to slide on the bed-flanges, said horse-heads having depending side flanges, 60 wedges held between the flanges of the horse-heads, a screw extending vertically through the wedges and heads, and removable legs held between the wedges and the flanges of the heads, substantially as described. 65

6. The combination, with the bed provided with leg-supporting heads, each having side flanges, of a wedge between said flanges, leg-receiving spaces being formed between the adjacent sides of the wedge and flanges, and 70 an operating-screw for the wedge, substantially as shown and described.

7. The combination, with the head 13, recessed on its upper end, provided with depending side flanges 14 14, and a central screw-threaded aperture, of a vertically-apertured wedge 15 between the said flanges and of less width than the space therebetween, a screw extending up through the wedge into the screw-threaded aperture, and a nut on the 80 screw bearing against the lower face of the wedge, substantially as shown and described.
